UNITED STATES PATENT OFFICE.

EBERHARDT A. VETTER, OF RICHMOND, VIRGINIA, ASSIGNOR TO CRAWFORD MANUFACTURING CO. INC., OF RICHMOND, VIRGINIA, A CORPORATION OF VIRGINIA.

CURTAIN BRACKET.

Application filed November 21, 1925. Serial No. 70,561.

This invention relates to curtain attachments for automobiles, and particularly to improved means for applying said curtains to the doors of automobiles so that the curtains will follow said door in the opening and closing movements thereof, even when said doors are pivotally mounted on a non-vertical axis.

It is old in the art to mount curtains to extend above the swinging doors of an automobile, so that said curtains will follow the door as it pivots around its hinges, thereby permitting unobstructed egress or ingress for passengers. When the doors of the automobile are mounted on hinges which are in straight vertical alignment, the opening pivotal movement of the door causes it to extend laterally of and at an angle to the body of the car, the curtain merely bending upon itself along a vertical line drawn through the axis of the aligned hinges, since, under such circumstances, there is no strain upon the fabric of the curtain.

Upon certain automobiles, of the present day, the doors thereof are pivotally mounted upon hinges which are not in exact vertical alignment, the lower hinge being positioned at one side of a vertical line drawn through the center of the top hinge. In most cases such structure is caused by the provision of an inwardly curved body, the curve beginning below the upper door hinge, the result being that the lower hinge is set inwardly with respect to the upper hinge. Since the top of the door at all times forms the same angle with the line of the two hinges thereof, it is obvious that, in doors so mounted, when the door is fully opened, the outer corner thereof is lower than the corner adjacent the car, and that said outer corner, moving outwardly and downwardly, comes to rest at a point which is further away from the front bow of the car than would be the case if the hinges were positioned in vertical alignment. Since it is also true that, in all cases on certain cars the stationary portion of the curtain is affixed to the body of the automobile in front of the door, and extends upwardly and is secured to the front bow above the windshield, it follows that the curtain structures at present in use would be ruptured by opening the

door, in the absence of any preventative curtain and door connecting devices.

It is therefore the object of the present invention to provide co-operating curtain-supporting means carried by the swinging door and the front bow of the automobile, which means are operative to permit free swinging movement of the curtain when mounted on doors hinged on either a vertical or non-vertical axis, said means being automatically operable to prevent rupture of the curtain fabric even though the door is hinged on a non-vertical axis.

Other objects of the invention will be made apparent in the accompanying specification, when read in connection with the drawings forming a part thereof.

In said drawings:

Fig. 1 is a fragmentary plan view of an automobile equipped with my invention, looking through the car and showing the curtains applied to the right hand side.

Fig. 2 is an enlarged fragmentary lateral section through the fabric of the top, showing the side and front bow, and the applied curtains.

Fig. 3 is an enlarged fragmentary perspective view, partly in section, showing my invention applied to the upper portion of the curtain.

Fig. 4 is a perspective view looking downwardly upon the connecting means forming the subject matter of my invention, the automobile top being removed.

Fig. 5 is an enlarged perspective view of the door bracket forming a part of my invention, and showing a portion of the upright curtain-supporting rod which extends into said bracket.

Fig. 6 is a detailed perspective view showing in full lines the position of an opened door mounted on non-vertical hinges, and in dotted lines, the position of an opened door mounted on vertical hinges, and,

Fig. 7 is a perspective view of one of the brackets forming part of my invention.

Now referring specifically to the drawings, in which similar reference numerals indicate like parts throughout the several views, A indicates the body of an automobile equipped with front doors B and rear doors C, as shown in Fig. 1. The customary top

1 is mounted upon bows 2 which extend longitudinally of the car and are curved at the front to provide a portion 3 just above the windshield 4. The present invention 5 contemplates means for properly securing a curtain 5 to the front doors B carried by the body A. In my companion application filed of even date herewith, I disclose means for applying rear curtains to the rear 10 doors C.

In order to better disclose the invention Fig. 1 shows an automobile in which the curtains on the left of the car have been removed, but the curtains on the right are in position. In the present drawings the invention is shown applied to a car of the Ford type, but it is obvious that the invention is equally applicable to any make of car.

Secured to the inside of the front door B, 20 is a socketed bracket 7, provided with an inturned lip 8 adapted to be secured to the top of the door by a screw or bolt. The lower portion of the bracket 7 extends downwardly, lying flat against the inner face of the door B, and terminating in two perforated ears 9 adapted to receive screws to fasten the bracket in position to the said door. The bracket is provided with converging flanges 10, which provide a socket 30 adapted to receive and retain the lower portion of a curtain rod 11, as shown in Fig. 5. The rod 11 extends upwardly through a hem provided in the rear side of the curtain 5, as clearly indicated in Fig. 1, the upper end of said rod being inserted into a socket provided in a retaining plate 12 secured to the top of the curtain. The upper portion of the curtain 5 is made in two folds, and slits are provided therein to permit the insertion 40 of a rod arm 13 which is rigidly secured at its rear end to the plate 12, the front end of said arm being extended through the double fold of the curtain, and terminating in an inwardly extending, curved offset portion 14, carrying a hooked end 15, as clearly shown in Fig. 3.

The upper edge of the curtain 5, at the point where it makes the turn to conform to the curvature of the bow 3, is provided with 50 a vertically extending slit 16. A plate 17 is secured to the bow 3, behind the curtain 5, said plate carrying a fastener element 18 adapted to extend through a registering eyelet 19 carried by the curtain. To the lower portion of plate 17 is connected an outwardly extending flange 20, and a link 21 is pivoted at 22 to said flange. The extreme outer end of the link 21 is perforated to receive the hooked end 15 of the arm 14, all of the structure just described being clearly shown in Figs. 3 and 7.

With the curtain mounted as above set forth the door B may be opened and the curtain will be bent upon itself substantially 60 upon the line of the slit 16, or in front

thereof. If the door is mounted on hinges positioned in vertical alignment, it will assume the position shown in dotted lines in Fig. 6. If the hinges 23 and 24 are not in vertical alignment however, as shown in 70 full lines, Fig. 6, the top corner α of the door B will drop downwardly to a point further away from the fastener 18 on the bow, 3, as will be understood. Such movement of the door would cause a rupturing strain 75 upon the curtain fabric. The present invention eliminates such danger in providing the structure shown in Fig. 2. When the door is swung outwardly the rod 11 carries with it the plate 12 and the rear end of the 80 arm 13, causing the curved end 14 of said arm to assume the position shown in dotted lines, Fig. 4. Such movement causes the link 21 to turn upon its pivot to the dotted line positions shown in Figs. 3 and 4, the 85 projection 25, carried by the flange 20, limiting the swinging movement of said link 21, and the walls defining the slit 16 separating sufficiently to compensate for the drop 90 of the corner α of the door. The strain is 95 upon the bottom of the slit 16, which may be heavily reinforced at this point to preclude the probability of rupture. Immediately upon closing the door the walls of the slit 16 assume their normal position, as 100 shown in Fig. 3, and the link 21 returns to the full line position shown.

From the foregoing it will be evident that I have provided a structure which, while not interfering with the operation of curtains carried by doors of the ordinary type, will prevent rupture of curtains carried on doors pivotally mounted on hinges positioned in non-vertical alignment. In some cases the curtains are applied to the right hand doors 105 only, and stationary curtains are mounted upon the doors at the left of the car.

Modifications of the structure herein illustrated will be suggested to those skilled in the art, but my invention covers all modifications falling fairly within the scope of 110 the appended claims.

What I claim is:

1. Means for mounting curtains on swinging doors of automobiles, comprising a rod 115 secured to a door and extending upwardly in substantial parallelism therewith, a curtain secured to said rod, an arm connected at one end to the upper portion of said rod and offset at its other end, said arm extending transversely of said rod and secured to the upper portion of said curtain, and means for pivotally securing the offset end of said arm to a fixed portion of the automobile, said means comprising a link pivotally secured at one end to said fixed portion of the automobile, and having its other end pivotally connected to said arm.

2. Means for mounting a curtain on an 125 automobile door carried by hinges arranged 130

in a non-vertical alignment, comprising a rod secured to the door and to one side edge of the curtain, an arm secured at one end to the top of said rod and connected to the top edge of the curtain, a plate secured to a fixed portion of the automobile and provided with a laterally extending flange, a link pivotally secured at one end to said flange and at the

other end to the free end of said arm, means on the flange limiting the pivotal movement of said link, and a slit formed in the upper edge of said curtain, adjacent said link, substantially as and for the purpose set forth.

In testimony whereof I affix my signature.
EBERHARDT A. VETTER.
